MANUALLY PROPELLED WATER SHOES
Samuel Ross Fines, 401 Parkside Drive, Toronto,
Ontario, Canada
Filed Sept. 21, 1959, Ser. No. 841,063
3 Claims. (Cl. 9—310)

This invention relates to sporting devices and, more particularly, to water shoes of the type designed to be propelled through the water by the use of ski poles or drawn through the water by a motorboat.

The sport of water-skiing has become increasingly popular among people skilled in this art but has certain disadvantages in that only persons with a considerable agility, balance and swimming ability are able to indulge in this sport.

Pontoons of various kinds have been devised to make the sport of water-skiing adaptable to be practised by persons less skilled in this art, but such pontoons have had the disadvantage of being cumbersome and difficult to manoeuvre.

Other water skis have been devised containing rudder attachments guided by lines held by the skier or by tipable foot rests that, upon being tipped forward, would turn the rudder to one side, and upon being tipped backward, would turn the rudder to the other side. These systems have the disadvantage that tipping of the skis during the skiing procedure will involuntarily turn the rudder when this is not desired or involuntary pull on the lines during the skiing procedure will cause undesired turning of the rudder, causing spills, etc.

It is an object of this invention to provide a water shoe in the configuration of a pontoon which will have automatic rudder means.

It is another object of this invention to provide a water shoe supplied with rudder means that will not involuntarily be actuated.

It is another object of this invention to provide a water shoe in the form of a pontoon in which the foothold is situated below the centre of gravity of the pontoon, tending to keep the pontoon upright at all times.

It is another object of this invention to provide a water shoe in the form of a pontoon in which tipping of the body of the water-skier to one side will automatically cause the water shoe to veer to the same side.

It is furthermore an object of this invention to provide a water shoe in the form of a pontoon in which the rudder means automatically will straighten out the direction of the water shoe as the body of the operator is brought upright.

It is another object of this invention to provide a water shoe in the form of a pontoon with automatic rudder means in which flow of water past said rudder means is utilized in aiding said rudder means to change the direction of the water-ski as it is propelled through the water.

It is also an object of this invention to provide water shoes in the form of pontoons that may be propelled over the water by water-ski staves supplied with pertinent thrust means at one end, adapted to be forcefully thrust against the water to propel the water-skier forward.

It is another object of this invention to provide water shoes in the form of pontoons with automatic rudder means in which the automatic change of direction can be assisted, put out of action or counteracted by the skier at will as he leans to one side, tipping the water shoes sideways.

These and other objects and features of this invention will become apparent when taken in conjunction with the following drawings in which:

FIG. 1 is a perspective view of the skier utilizing a pair

2

of water shoes embodying this invention being drawn through the water by a motorboat or similar vehicle.

FIG. 2 is a perspective view of a skier utilizing a pair of water shoes embodying this invention, propelling himself through the water by aid of water-ski poles as embodied in this invention.

FIG. 3 is a mid-vertical sectional side elevation of a water shoe embodying one configuration of this invention.

FIG. 4 is an end elevation of the water shoe shown in FIG. 3.

FIG. 5 is a reverse plan view of the water shoe shown in FIG. 3.

FIG. 6 is a side elevation of a water shoe embodying another configuration of this invention.

FIG. 7 is a reverse plan view of the water shoe shown in FIG. 6.

FIG. 8 is a side elevation of a water shoe embodying a third configuration of this invention.

FIG. 9 is a reverse plan view of the water shoe shown in FIG. 8.

FIG. 10 is a side elevation of a water shoe embodying a fourth configuration of this invention.

FIG. 11 is a reverse plan view of the water shoe shown in FIG. 10.

FIG. 12 is a mid-vertical part-sectional side elevation of a water-shoe pole embodied in this invention comprising a buoyant pole end.

FIG. 13 is a plan view of the water-shoe pole shown in FIG. 12.

FIG. 14 is a mid-vertical part-sectional side elevation of a water-shoe pole embodied in this invention comprising an open cup end attached to the pole through a universal joint.

FIG. 15 is a plan view of the water-shoe pole shown in FIG. 14.

FIG. 16 is a side view of a third configuration of a water-shoe pole embodied in this invention comprising a cup-shaped end attached rigidly to the pole.

FIG. 17 is a plan view of the water-shoe pole shown in FIG. 16.

Referring first to FIG. 1, a person 1 is shown being drawn by, for instance, a motorboat through handle 2 while utilizing a pair of water shoes 3 and 4 embodying one configuration of this invention comprising a flexible rudder 5 flexibly attached at 6 to keel 7 of water shoe 4, flexible rudder 5 being free to move sideways under water shoe 4 from point of attachment 6 to the opposite end of flexible rudder 5, said opposite end being loaded with a weight 8 adapted to swing the loaded end of flexible rudder 5 to one side or the other through force of gravity, upon water shoe 4 being tipped to one side or the other. Both water shoes of the pair are of identical configuration, water shoe 3 containing a flexible weighted rudder 9 identical to flexible rudder 5 on water shoe 4.

Water shoes 3 and 4 are watertight and buoyant being hollow and filled with air or made of buoyant material. The person 1 utilizing water shoes 3 and 4 places his right and left foot into hollow compartments 10 and 11 respectively, resting his feet in a suitable foothold in each of compartments 10 and 11 at a location below centre of gravity of water shoes 3 and 4, the footholds being adapted to slip off the feet easily upon the person 1 encountering a spill.

The person 1 being drawn through the water by a motorboat, upon requiring to turn to one side or the other, needs only lean to the side to which he requires to turn, tipping water shoes 3 and 4 to the required side, causing the weighted ends 8 of flexible rudders 5 and 9, through action of gravity thereon, to swing out to the same side, thereby creating a drag on the water rushing past the water shoes on the turn side, and a suction

effect on the opposite side of flexible rudders 5 and 9 causing the water shoes to turn in the required direction.

Referring to FIG. 2, a person 12 is shown utilizing a pair of water shoes 13 and 14 embodying this invention, propelling himself through the water by the aid of a pair of water-shoe poles 15 and 16 embodied in this invention.

By placing cup ends 17 and 18 on the surface of the water and thrusting backwards on cup ends 17 and 18 through poles 15 and 16, person 12 will propel himself through the water being held up by buoyant water shoes 13 and 14 of configuration as explained above in FIG. 1.

Turning or curving in course of progression on these water shoes 13 and 14 can be accomplished by thrusting more powerfully on one pole than on the other, the person 12 at the same time tilting his body and the water shoes to the side to which he requires to turn, whereby weighted flexible rudders 19 and 20, through action of gravitational force, will swing to the turn side, thereby facilitating turning action of the water shoes.

With reference to FIGS. 3, 4 and 5, a buoyant water shoe 23 is shown embodying a footwell 24 located substantially centrally along the length of water shoe 23 and adapted to receive internally of its bottom surface a suitable foothold 25. Situated co-incident with the longitudinal centre line of the water shoe 23 and rigidly attached to the bottom surface of water shoe 23 in conventional manner is a keel 26 terminating at its aft end 27 in a hingeably attached flexible rudder 28 which is attached to the water shoe only at keel end 27 and has rigidly attached to its extreme aft end, a streamlined weighted mass 29.

Flexible rudder 28 is therefore free to swing sideways with its aft end as dictated by weight 29 and is through conventional aligning means adapted to align itself automatically parallel with the direction of keel 26 at times when no gravitational forces act to flex rudder 28 sideways.

Referring to FIGS. 6 and 7, another method of embodying this invention in a water shoe is shown comprising buoyant water shoe 30 fitted with a footwell 31 and keel 32. A rudder 33 of substantially non-flexible material is rotatably mounted on a shaft 34 which is rigidly and perpendicularly attached below water shoe 30 and located in a plane containing keel 32, rudder 33 being mounted on shaft 34 at a location forward of the longitudinal centre of rudder 34. A streamlined weighted mass 35 is rigidly attached to the extreme aft end of the rudder 33.

A further method of embodying this invention in a water shoe is shown in FIG. 8 and FIG. 9 in which a buoyant water shoe 36 embodies a footwell 37 and keel 38. A rudder 39 of substantially non-flexible material is rotatably mounted on a shaft 40 which is rigidly attached below water shoe 36 in a plane containing keel 38, and at an angle inclined to the perpendicular with the bottom of water shoe 36, rudder 39 being mounted on shaft 40 at a location forward of the longitudinal centre of rudder 39, a streamlined weight 41 being rigidly secured to the extreme aft end of rudder 39.

Action of rudder 33 in FIGS. 6 and 7 and rudder 39 in FIGS. 8 and 9 depends on weights 35 and 41 respectively, rudders 33 and 39 being held in a plane common to keels 32 and 38 respectively, partly through action of the water flowing by the water shoes as these are driven straight ahead and partly by gravitational force acting straight downward. Upon water shoes 30 and 36 being tipped sideways, gravity acting on weights 35 and 41 will force the aft end of rudders 33 and 39 respectively to move to the side to which the water shoes are tipped, thereby creating a drag on the water at that side of the water shoe tending to turn the water shoes in the direction towards which the water shoe is tipped.

As aft portion of rudders 33 and 39 are turned toward the tipped side of the water shoe, the forward end of rudders 33 and 39 will turn to the opposite side, thereby entering the stream of water passing along the opposite

side of the water shoe, this water therefore being deflected along the rudders 33 and 39 giving an added turning moment to the water shoe in the direction towards which this is tipped. Thus it is seen that upon tipping the water shoes to one side, the weights will swing the rudders to the same side, whereby the forward edges of said rudders are caused to engage the stream on the opposite side, this additional water resistance providing a hydrodynamic counterbalance to some of the water resistance arising on the weighted (i.e. tilted) side, thereby canceling some of the turning moment opposing that of the tilted weight, to facilitate the action thereof. Turning moment of rudders 33 and 39 can be varied by varying the inclination of shafts 34 and 40 respectively and by varying the location of shafts 34 and 40 with respect to the longitudinal centre and the forward end of rudders 34 and 39.

Another method of embodying this invention in a water shoe is shown in FIG. 10 and FIG. 11 in which a buoyant water shoe 42 is shown embodying a footwell 43. A foothold 44 is rotatably located in well 43, being rigidly secured to a vertical rotatable shaft 45 which projects vertically downward through a watertight seal in the bottom of water shoe 42. Rigidly attached to the lower end of shaft 45 is a rudder 46 attached to shaft 45 at a location forward of its longitudinal mid-point. The keel 47 is located below water shoe 42 in a vertical plane common with the neutral position of rudder 46 and interrupted for a portion of its length to accommodate rudder 46 and permit rudder 46 to turn to either side. One end of rudder 46 is loaded by a weight 48 upon which gravity may act to provide automatic action of rudder as water shoe is tipped to one side or the other.

A water-skier using the water shoe 42 would place his foot on foothold 44. By tipping water shoe 42 sideways as it moves forward, gravity acting on weight 48 would tend to turn the rudder and thereby change direction of the water shoe. By twisting his leg, the water-skier could permit the foothold to turn, through the gravitational force, giving him the possibility of controlling the turning radius of the water shoe 42 by holding back against the gravitational pull on weight 48 or by aiding the gravitational pull by twisting his legs more than dictated by the gravitational pull on weight 48, thereby permitting the skier to counteract the turning action caused by the gravitational pull on the rudder weight 48 upon tipping shoe sideways and permitting him to continue straight forward even though water shoes are tipped sideways, or to exaggerate the turning moment if so required.

In all cases described above in FIGS. 3-11, the normal positions for rudders 28, 33, 39 and 46 would be a position parallel to the longitudinal axis of water shoes 23, 30, 36 and 42 which would be parallel to the direction of motion of the water shoes through the water. Action of water streaming past the sides of the water shoes will automatically keep all rudders in this normal position as long as no gravitational force acts to turn the rudders to one side or the other. Thus, only a conscious act on the part of the skier such as tipping water shoes to one side or the other would cause the rudders to turn and thus change direction of the water shoe. Thereby, spills in the water due to uncontrollable actions on the part of the skier are avoided.

In order to propel the water shoes embodying this invention through the water, a pair of water-shoe poles are utilized adapted to be held one in each hand having thrust means attached to the lower end of each water-shoe pole adapted to be thrust against the surface of the water in order to create a reaction adapted to propel the water-skier and the water shoes over the surface of the water.

A water-shoe pole embodied in this invention is shown in FIG. 12 and FIG. 13 comprising a substantially pole-shaped member 49 having a strap 50 attached to one end adapted to be held by the hand or the wrist when pole 49 is grasped at its upper end. The end of pole member

49 opposite to the end attached to strap 50 has a buoyant watertight tank 51 located rigidly secured to pole 49. Volume of tank 51 is such as to provide sufficient buoyancy on the water's surface combined with surface area on the bottom of the tank 51 to provide sufficient reaction force for the water-skier to propel himself forward by thrusting against the surface of the water through pole 49 and tank 51.

Another method of embodying this invention in a water-shoe pole is shown in FIG. 14 and FIG. 15, in which pole member 52 is supplied at its upper end with a strap 53, having at its lower end a universal swivel joint 55 to which an inverted cup 54 is attached, cup 54 being adapted to be thrust against the surface of the water, trapping air therein and giving a firm resistant thrust action on the surface of the water to provide propelling action for the water-skier.

Referring to FIG. 16 and FIG. 17, another method of embodying this invention in a ski pole is shown wherein the water-shoe pole member 56, having at its upper end a strap 57, the lower end of pole 56 terminating in a foldable umbrella-like inverted cup 58 attached to the lower end of pole 56. The umbrella-like cup 58 has the advantage that during the thrusting motion, the cup would be extended to its full diameter trapping air on the surface of the water and supplying a large end area for water resistance, whereas the umbrella-like cup, upon being withdrawn upwards from the water, is adapted to fold together to facilitate such withdrawal from the water.

It will be understood that the design of the water shoes and water-shoe poles embodied in this invention can be varied while still retaining the novel features of this invention and the side action of the rudders embodied in this invention can be limited in their turning movement by conventional means to prevent excess turning of the 35 water shoes which might create a spill hazard for the water-skier.

The embodiments of the invention in which an exclu-

sive property or privilege is claimed are defined as follows:

1. Manually propelled water shoes comprising a pair of identical buoyant elongated pontoon bodies, each body of said shoes having a keel attached vertically thereunder, parallel to the longitudinal axis thereof, a well sunk into the top of said body, said well being located substantially centrally of the longitudinal axis thereof, foothold means attached at the bottom of said well at a location below 10 the centre of gravity of said body, hingeably attached rudder means located below said body, hinge axis of said hingeably attached rudder means being located in a plane common to a plane containing said keel, said hinge axis being located intermediate the two ends of said rudder means to provide a substantial but smaller portion of said rudder means forward of said hinge axis for hydrodynamic counterbalancing purposes, and a larger rudder means portion aft of said hinge axis and weight means attached substantially toward the aft end of said rudder means.
2. Manually propelled water shoes as claimed in claim 1 in which said hinge axis of said rudder means is located perpendicular to the longitudinal axis of said shoe.
3. Manually propelled water shoes as claimed in claim 25 1 in which said hinge axis is inclined from perpendicularity with said longitudinal axis of said shoe.
